UNITED STATES PATENT OFFICE.

FRANK H. STANWOOD, OF WILMETTE, ILLINOIS, ASSIGNOR TO STANWOOD EQUIPMENT COMPANY, OF CHICAGO, ILLINOIS, A CORPORATION OF ILLINOIS.

FOOT SCRAPER FOR AUTOMOBILE RUNNING BOARDS.

Application filed March 6, 1924. Serial No. 397,176.

To all whom it may concern:

Be it known that I, FRANK H. STANWOOD, a citizen of the United States, residing in Wilmette, in the county of Cook and State 5 of Illinois, have invented a new and useful Improvement in Foot Scrapers for Automobile Running Boards, of which the following is a specification.

My present invention relates to a foot 10 scraper for automobile running boards and has for a principal object the provision of a scraper adapted to be positioned in the body of the running board at a convenient position for use by a person entering the 15 car.

I am aware that foot scrapers of various types have been provided at the edge of automobile running boards by attachment of a suitable part to the outer face of said 20 board. These devices, however, have not been very satisfactory in service, due to the inconvenience of use, since they require the user to turn around, or assume an unnatural position in entering the car. An 25 other disadvantage is that a protruding scraper is likely to be broken off, or damaged, by being struck by another car, or otherwise. The purpose of my invention, therefore, is to provide a foot scraper at 30 a position and of such character that it may be readily used from the natural position of a person entering the car.

It is also an object of the invention to 35 provide a foot scraper having the foregoing advantages which will be strong and durable and which will provide a metal lining and edging for the opening in the running board in which it is positioned, thus preventing damage to the board and 40 covering at this point.

A further object of the invention is the provision of a running board foot scraper 45 which will be of pleasing appearance and will add to, rather than detract from the ornamentation of the car.

Numerous other objects and advantages 50 of the invention will be apparent as it is better understood from the following description, which, taken in connection with the accompanying drawings, disclose a preferred embodiment thereof.

Referring to the drawings,

Figure 1 is a perspective view of a running board provided with a foot scraper 55 embodying the principles of my invention,

the portions of the car to which said running board is attached being partially and diagrammatically shown;

Fig. 2 is an enlarged partial section taken through the scraper longitudinally of the 60 running board; and,

Fig. 3 is a similar section taken transversely of the running board.

The running board 21, which is secured to the body 22 and fender 23 of the car, 65 may be of any usual character and, in the present instance, is provided with a covering 24 and an edging 25. Near the forward end of said running board there is provided a transverse opening 26 in which 70 the scraper, now to be described, is positioned.

Said scraper comprises a hollow metal member composed of separable parts 27 and 28, said parts being drawn together by 75 the means of screws 29 extending up from the bottom through aligned bosses 31 and 32 in said parts 27 and 28. Said parts are provided, respectively, with laterally extending flanges 33 and 34 adapted to be clamped 80 against the top and bottom of the running board when the screws 29 are tightened. A transverse ridge, or scraper element, 35 is provided upon the upper section 27 of 85 the scraper member at the rear of the opening.

It will be evident that a person entering the car may make use of the scraper while standing on the running board and facing 90 forwardly and with but slight change of position. The dirt will fall through the opening provided adjacent the scraper element 35 and the wall of the aperture 26, as well as the edges of the covering 24, are 95 thoroughly protected.

It is thought that the invention and many 100 of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A foot scraper for automobile running boards and the like, comprising a two-piece hollow metal member positioned in an opening in the body of the running board and 110

having an upstanding scraper part thereon, the pieces of said member having outwardly extending flanges adapted to engage respectively the upper and lower sides of the running board.

2. A foot scraper for automobile running boards and the like, comprising a two-piece hollow metal member positioned in an opening in the body of the running board and

having an upstanding scraper part thereon, the pieces of said member having outwardly extending flanges adapted to engage respectively the upper and lower sides of the running board, and means for drawing said parts together to clamp said flanges against said running board.

FRANK H. STANWOOD.
